UNITED STATES PATENT OFFICE.

FRAZER LOUIS JETER, OF NEW ORLEANS, LOUISIANA.

SAMPLE CASE AND CATALOGUE-SHEET CARRIER.

Application filed February 14, 1924. Serial No. 692,701.

To all whom it may concern:

Be it known that I, FRAZER L. JETER, a citizen of United States, residing at New Orleans, Louisiana, have invented certain new and useful Improvements in Sample Cases and Catalogue-Sheet Carriers, of which the following is a specification.

This invention relates to a sample and catalogue sheet case particularly adapted for use by traveling salesmen in carrying samples and loose leaf catalogue sheets.

One important object of the invention is to provide a case of this description having a substantial flexible envelope and a loose leaf binder arranged in such relation that the binder may be folded flat upon the envelope when not in use, the envelope being provided with a removable stiffener adapted for use as a sample support. The whole being of an improved and novel construction.

With the above and other objects in view as will be hereinafter apparent, the invention consists in general of certain novel details of construction and combinations of parts hereinafter fully described, illustrated in the accompanying drawings and specifically claimed.

In the accompanying drawings like characters of reference indicate like parts in the several views, and:

Figure 1 is a view in elevation of one side of the device, with the binder folded and out of sight.

Figure 2 is a view of the other side of the device with the binder dropped for use.

Figure 3 is an end view of the device, the binder being shown in position for use in full lines and in the position assumed when out of use in dotted lines.

Figure 4 is a detail section on the line 4-4 of Figure 2.

In the embodiment of the invention herein illustrated there is shown an envelope 10 having the outer flap 11 secured by fasteners 12. A handle 13 is provided for carrying this envelope. The back of the envelope is extended down and then at right angles to form a back 14 for a loose leaf binder 15 having tubular leaf securing elements 16 extending transversely of said back and so secured thereto as to stiffen the same. By

this construction the back of the envelope at the point 16 forms a species of hinge so that the binder may be placed either in the position shown in full lines in Figure 3 or in the dotted line position in that figure. Furthermore, there is provided in the envelope a removable stiffener 17 which serves to hold the envelope rigid when inserted therein and this stiffener may, if desired, be provided with loops 18 for carrying samples. Thus the device is particularly adapted for silverware and cutlery samples.

In use, the salesman starts out with the loose leaf binder filled with catalogue sheets and as he goes from place to place these sheets may be removed until the sheets are exhausted. The sheets will be held, during transportation, by an ordinary strap and buckle, as indicated at 19 and 20, and in like manner this strap may be used to hold the binder folded when the sheets are exhausted.

There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within the scope claimed.

Having thus described the invention, what is claimed as new, is:

A device of the kind described including a stiff loose leaf carrying portion consisting of two parts fixedly arranged at right angles to each other, one of the parts being relatively narrow and the other relatively wide, loose leaf carrying rods projecting from the narrow portion and extending parallel to the wide portion, a cover member hinged to the narrow part on the edge opposite the wide part, and an envelope carried by the side of the cover member adjacent the leaf carrying portion and slightly spaced from the hinge whereby the leaf carrying portion may be folded to lie against said envelope.

In testimony whereof I affix my signature.

FRAZER LOUIS JETER.
